[57] CLAIM

The ornamental design for a cookie caddy, as shown and described.

DESCRIPTION

FIG. 1 is a perspective view of a cookie caddy showing my new design;

FIG. 2 is a plan view of the grasping mechanism in an open position;

FIG. 3 is an elevation view of the grasping mechanism in a closed position; and,

FIG. 4 is a side view of one of the grasping members.

The grasping mechanism is shown separately in FIGS. 2 and 3 and the inner portion of one of the grasping members shown separately in FIG. 4 for clarity of illustration.
